UNITED STATES PATENT OFFICE.

HERMANN KUPSCHE, OF CHICAGO, ILLINOIS, ASSIGNOR TO ALTON F. JOHNSON, OF CHICAGO, ILLINOIS.

FAUCET OR COCK.

SPECIFICATION forming part of Letters Patent No. 761,973, dated June 7, 1904.

Application filed May 11, 1903. Serial No. 156,701. (No model.)

To all whom it may concern:

Be it known that I, HERMANN KUPSCHE, a citizen of the United States, residing at Chicago, in the county of Cook and State of Illinois, have invented certain new and useful Improvements in Faucets or Cocks; and I do hereby declare the following to be a full, clear, and exact description of the invention, such as will enable others skilled in the art to which it applies to make and use the same.

My invention relates to a novel construction in a faucet or cock, the object being to provide a slow-closing cock in which pounding due to sudden shutting off is entirely avoided and in which the flow of water can be regulated at will; and it consists in the features of construction and combinations of parts hereinafter fully described and claimed.

In the accompanying drawings, illustrating my invention, Figure 1 is a central vertical section of a faucet or cock constructed in accordance with my invention, showing the valve closed. Fig. 2 is a similar section showing the valve open.

Referring now to said drawings, A represents the water-inlet, B the water-outlet, and C a horizontal valve-seat interposed between the water inlet and outlet and surrounding the opening establishing communication between said inlet and outlet. Above said valve-seat C is a vertical cylindrical chamber D, in which a trunk piston-valve E is longitudinally movable, said valve being of larger diameter than said valve-seat and seating thereon. A cylindrical extension F on the lower end of said valve E enters said opening surrounded by said valve-seat C. The upper end of said chamber D above said valve E forms a fluid-pressure chamber which communicates with the water-supply through passages G and H in valve E, said passage G being radial and opening into a groove I in the periphery of said valve extending from the lower end of the latter to a point just above the mouth of said passage G. The passage H is central and opens into the hollow upper end of said valve E. The upper end of said chamber D is enlarged and internally threaded, the shoulder at the lower end of said enlarged portion form-

ing a seat for the lower end of a sleeve J, which enters said enlarged portion of said chamber D. At its lower end said sleeve J is provided with a peripheral groove K, which communicates by means of radial passages L with the central opening M of said sleeve. The latter is screw-threaded to receive the threaded valve-stem N of a valve O, seating on a valve-seat P, formed in the lower end of said opening M of said sleeve. Below said valve O is a second stem or projection Q, of smaller diameter than the opening R, surrounded by said valve-seat P. A by-pass duct S in the body of the valve-casing connects the annular chamber formed by said groove K with the outlet B.

The operation of my device is as follows: When the valve O is closed, the pressure in the chamber above the valve E is equal to the service-pressure, and by reason of such pressure acting on a larger surface at the upper than at the lower end of said valve the latter is held firmly closed by the excess of pressure on its upper end. As soon as said valve O is opened and the pressure on the upper end of the valve released the latter will be instantly raised, the water displaced by said movement passing out through the duct S. As said valve E rises it strikes the projection Q, which limits its upward movement, so that the initial opening of said valve is so limited as to admit of only a limited flow of water. By further revolving the valve-stem N the latter and said projection Q are raised and the valve E follows, thereby gradually increasing the flow of water. There will be a very slight flow of water through the passages G and H and duct S; but by reason of the very limited size of the passage G such flow is insufficient to produce a pressure above the valve E, so that there can be no leaking at the upper end of the sleeve J or enlarged portion of the chamber D. Hence it is unnecessary to provide stuffing-boxes to prevent leakage. As said valve O is again closed the valve E will slowly close also partly by gravity and partly by accumulation of water in the chamber above said valve and the equalization of pressures on the differential areas. The valve-

stem N is turned by means of the button U at its upper end.

This faucet or cock has many advantages, the wearing parts being entirely protected 5 against misuse by the exercise of too much power by the operator and the flow of water being capable of regulation as desired, while sudden shutting off of the flow and consequent pounding are rendered impossible.

10 On said projection Q at its lower end is a nut or collar Q', which is adapted to prevent the valve-stem N from being entirely withdrawn.

I claim as my invention—

15 1. In a faucet or cock, the combination with a fluid-pressure-actuated piston-valve in the body thereof, and an auxiliary valve controlling the movements of said piston-valve, of a threaded sleeve in which the stem of said auxiliary valve moves, and a projection on said auxiliary valve adapted to limit the opening movement of said piston-valve to regulate the flow 55 of water.

20 2. In a faucet or cock, the combination with a fluid-pressure-actuated piston-valve in the body thereof, of an auxiliary valve controlling the movements of said piston-valve, and devices controlled by said auxiliary valve and engaging said piston-valve for limiting the 60 opening movement thereof to regulate the flow of water.

25 3. In a faucet or cock, the combination with a fluid-pressure-actuated main valve in the body thereof, of an auxiliary valve controlling the opening and closing of said main valve, and devices controlled by said auxiliary valve and engaging said main valve to control the 65 degree of opening thereof to regulate the flow of water.

30 4. In a faucet or cock, the combination with a fluid-pressure-actuated main valve in the

body thereof, and an auxiliary valve controlling the opening and closing of said main valve, of an adjustable stop controlled by said auxiliary valve and engaging said main valve when 45 open to limit the degree of opening thereof to regulate the flow of water.

5. In a faucet or cock the combination with a fluid-pressure-actuated main valve in the body thereof, of an auxiliary valve controlling 50 the opening and closing of said main valve, and a stop located in the path of said main valve and moving simultaneously with said auxiliary valve for limiting the degree of opening of said main valve and regulating the flow 55 of water.

6. In a faucet or cock, the combination with a fluid-pressure-actuated main valve in the body thereof, and an auxiliary valve controlling the opening and closing of said main valve, 60 of a movable stop located in the path of said main valve for limiting the degree of opening thereof, and operating means common to said auxiliary valve and said stop for opening said main valve and adjusting said stop. 65

7. In a faucet or cock, the combination with a fluid-pressure-actuated main valve in the body thereof, a valve-stem longitudinally movable in said body, and an auxiliary valve on said stem controlling the movements of said 70 main valve, of a projection on said valve-stem and auxiliary valve projecting into the path of said main valve and adapted to act as a stop to limit the opening movement of said main valve, whereby the flow of water can be 75 regulated.

In testimony whereof I affix my signature in presence of two witnesses.

HERMANN KUPSCHE.
